UNITED STATES PATENT OFFICE

GEORGE L. BAIR, OF HANOVER, PENNSYLVANIA

FLOOR CONSTRUCTION

Application filed September 15, 1931. Serial No. 562,944.

The present invention relates to a floor construction for buildings and has for some of its objects to provide, in a manner as hereinafter set forth, a floor which will be strong, durable, fire-proof, light in weight and which may be constructed at low cost.

All of the foregoing and still further objects and advantages of the invention will become apparent from a study of the following specification, taken in connection with the accompanying drawings wherein like characters of reference designate corresponding parts throughout the several views, and wherein:—

13 Figure 1 is a top plan view showing an embodiment of a floor constructed in accordance with the present invention.

Figure 2 is a view in vertical section taken substantially on the line 2—2 of Figure 1.

20 Figure 3 is a detail view in perspective showing a pair of blocks which constitute the important elements of the invention.

Figure 4 is a view in top plan showing a modification of the invention.

23 Figure 5 is a vertical sectional view taken substantially on the line 5—5 of Figure 4.

Figure 6 is a vertical sectional view taken substantially on the line 6—6 of Figure 4.

Referring now to the drawings in detail, 30 it will be seen that the reference numeral 1 designates pairs of hollow blocks of suitable material which are open on one side only and which include the thin and comparatively thick horizontal walls 2 and 3, respectively.

35 The hollow blocks 1 further include a reinforcing rib 4 extending transversely therein from the open side to the closed side thereof.

The pairs of blocks 1 are arranged with the open sides thereof in abutting engagement with each other so that said pairs of blocks communicate. The pairs of blocks, 40 as seen in Figure 1 of the drawings, are arranged in spaced, parallel rows on suitable forms and reinforcing bars 5 are arranged

45 between the rows. When arranging the blocks in the rows the comparatively thick walls 3 of certain of the pairs are disposed uppermost and the comparatively thick walls 3 of the other pairs are disposed lowermost, as illustrated to advantage in Figure

2 of the drawings. This is for the purpose of taking care of compression and tension in the completed floor.

Concrete or other suitable material is then 55 poured between the pairs of blocks to form the joints 6 and the supporting beams 7. The joints 6 are flush with the upper and lower surfaces of the blocks 1, it being unnecessary to provide a layer of concrete either above or below the blocks. This 60 constitutes a most important and desirable feature of the invention.

In the modified form of the invention illustrated in Figures 4, 5 and 6 of the drawings adjacent pairs of the blocks are disposed at right angles. The opposed edges of the comparatively thick walls 3 of the pairs of blocks are formed with recesses which, in conjunction with each other, define channels or grooves 8 for the reception of the concrete or other joint forming material, as indicated at 9. In other respects, the modified 70 form of the invention is substantially the same as the form shown in Figures 1 to 3, inclusive, of the drawings.

The pairs of blocks may be arranged in any desired manner in the floor other than as shown in the drawings. For example, the pairs of blocks may be arranged diagonally with respect to each other. It may be well 80 to here invite attention to the fact that the channels 8 in Figures 4 to 6, inclusive, of the drawings also extend on vertical sides or ends of the pairs of blocks.

It is believed that the many advantages 85 of a floor constructed in accordance with the present invention will be readily understood, and although the preferred embodiments of the invention are as illustrated and described, it is to be understood that further modifications may be resorted to which will fall within the scope of the invention as claimed.

What is claimed is:—

1. A floor construction comprising pairs 90 of substantially hollow, complementary blocks, said blocks being open on one side and closed on the other sides, the open sides of the pairs of the blocks being disposed in abutting engagement with each other, said blocks includ- 100

ing comparatively thin and thick horizontal walls, and a joint of suitable material connecting the pairs of blocks together, certain of the opposed edges of the pairs of blocks having opposed recesses therein defining, in conjunction with each other, channels for the reception of the joint material.

2. A floor construction comprising pairs of substantially hollow, complementary blocks, said blocks being open on one side and closed on their other sides, the pairs of blocks having their open sides in abutting engagement with each other, said pairs of blocks being spaced from each other, said pairs of blocks including comparatively thin and thick horizontal walls, the comparatively thick horizontal walls of certain of the pairs of blocks being disposed uppermost, the comparatively thick horizontal walls of the other pairs of blocks being disposed lowermost, reinforcing rods extending between the pairs of blocks, and a cementitious joint disposed between the pairs of blocks for connecting said pairs together, certain of the abutting edges of the pairs of blocks having recesses therein defining, in conjunction with each other, channels for the reception of the joint material.

In testimony whereof I affix my signature.

GEORGE L. BAIR.
